UNITED STATES PATENT OFFICE.

WALTER EDWIN STEPHENSON, OF ROOSEVELT, NEW YORK.

MOTOR-RADIATOR AIR-DRAFT CONTROL.

1,220,794.

Specification of Letters Patent. Patented Mar. 27, 1917.

Application filed March 18, 1916. Serial No. 85,097.

To all whom it may concern:

Be it known that I, WALTER E. STEPHENSON, a citizen of the United States, and a resident of Roosevelt, in the county of Nassau and State of New York, have invented a new and Improved Motor-Radiator Air-Draft Control, of which the following is a full, clear, and exact description.

My invention relates to means for regulating the air circulation through the radiator of a motor vehicle. An object thereof is to provide a simple and inexpensive device whereby air may be caused to circulate through some part of the radiator while it is excluded from other parts. A further object of the invention is to provide a device of the class described whereby air may be caused to circulate through the entire radiator or prevented entirely from circulating through the radiator.

With the above and other objects in view, the nature of which will more fully appear as the description proceeds, the invention consists in the novel construction, combination and arrangement of parts as herein fully described, illustrated and claimed. In the accompanying drawings, forming part of the application, similar characters of reference indicate corresponding parts in all the views.

Figure 1 is a side elevation of a motor vehicle radiator provided with an embodiment of my invention, certain parts of which invention are broken away to show the details of construction, the air-draft control in this figure being shown obstructing the air circulation through the radiator.

Fig. 2 is a similar view showing the air-draft control of the radiator, permitting circulation through the upper part of the radiator while preventing air circulation in the lower part thereof.

Fig. 3 is a view similar to Fig. 1, showing the air-draft control in the position permitting partial obstruction of the circulation in both the upper and the lower parts;

Fig. 4 is a front elevation of the device shown in Fig. 3, the engine hood being shown in section about the device; and

Fig. 5 is a fragmentary enlarged section through the radiator and device.

Referring to the drawings, 6 is the radiator of the motor vehicle, of the common cellular structure, at the rear of which rectangular shutters 7 are disposed across the horizontal rows of the air cells 8 of the

radiator. Each shutter preferably terminates with a trunnion 9 at each end at the upper horizontal edge of the shutter. The trunnions bear in loops 10 formed in a strip 11 extended along the vertical bordering cells of the radiator. The strips between the loops are depressed into the air cells below the surface of the radiator, as best seen in Fig. 5. By the engagement of the trunnions with the loops, each shutter is hinged adjacent the upper part of the air cells 8. It is self-evident that any other suitable means may be provided for hinging the shutters 7 to the radiator.

Each shutter has an extension 12 at each end fitting into an individual diagonal slot provided in a slide 13 mounted along the ends of the shutters in suitable guides 14 secured to the radiator. It will be seen from Figs. 1, 2, and 3 that all the slots are open into the edge of the slide resting against the radiator so that the extensions 12 of the shutters may come in contact with the surface of the radiator, thereby allowing the shutter to come in contact with the surface of the radiator, thus perfectly closing the cells and obstructing flow of air therethrough. A number of the upper slots marked 15 are arcuate and are at a greater angle to the edge of the slide than the straight slots below marked 16.

The straight slots at the edge have a slot extension or cut-away 17 at an angle to the main portion of the slot whereby said slides 13 have an initial displacement relative to the extensions or shutters engaged by said slot 13 before said extensions are engaged by the straight sides 18 of the slots. In consequence the shutters engaged in the slots 15 are caused to operate, while those engaged in the slots 16 remain inoperative until they are engaged and moved by the continuous side 18 of the slots 16. Due to the lesser angularity of the slots 16, they displace the shutters engaged thereby more rapidly than the slots 15. Consequently, when the slides are totally displaced all the shutters are disposed at right angles to the surface of the radiator. This arrangement permits a partial displacement of the upper shutters 7 without the displacement of the lower shutters 7. In consequence air is allowed to circulate through the upper rows of cells in the radiator, while air is prevented from circulating in the lower row of cells. Therefore, there will

be more radiation in the upper or warmer part of the radiator. By this arrangement undue radiation or cooling of the water in the radiator may be prevented in winter.

5 In summer, when a perfect radiation is desired, all of the shutters are disposed at right angles to the surface of the radiator, thereby leaving the cells unobstructed. Furthermore, the shutters being of metal, when in such position they will increase the radiating surface of the radiator.

10 The movement of the slides 13 is controlled by a sliding block, preferably mounted on the radiator and connected to the slides by links 20 which are also pivoted on the radiator. By moving the block 19 up the slides are caused to descend. An initial displacement of said slides upwardly will cause the operation of the shutters engaged in the arcuate slots 15 until the extensions 12 engaged in the slots 16 of the slides come into engagement with the continuous side 18 of said slots. By locking the sliding block 19 in this position by means 15 of a butterfly screw 21, the upper shutters will be retained in a partially open position, while the lower shutters will remain inoperative, as shown in Fig. 2. If the sliding block 19 is moved so as to totally 20 displace the slides 13 upwardly all the shutters will be opened. The block 19 may be made to be operated from the seat of the driver if so desired, but this, not forming 25 part of the invention, is not illustrated.

30 I claim:

1. An air draft control for cellular radiators of motor vehicles, comprising a plurality of shutters each adapted to obstruct a row of cells, slides having slots engaged by 35 said shutters, means for operating the slides whereby the shutters are actuated, certain of said slots having an angular extension whereby said slides have initial displacement relative to the shutters engaged in the 40 slots having the extension, said slots having the extension being adapted to displace the shutters engaged therewith more rapidly than the other slots, whereby all the shutters can be fully displaced.

45 2. An air draft control for cellular radiators of motor vehicles comprising, a plurality of rectangular shutters disposed transversely of the radiator, each of said shutters being hinged at its upper edge along a 50 horizontal row of cells, a slide having diagonal slots open at the edge disposed along the ends of the shutters, each of said shutters having an extension engaging a slot in the slide, the slots in the slides engaging the 55 shutters in the lower half of the radiator having an angular extension whereby said slides have an initial displacement relative to the shutters in the lower half of the radiator, the angularity of said slots having an 60 extension being such as to cause a more

rapid displacement of the shutters engaged therein than that of the slots engaging the shutters in the upper half of the radiator, and means for actuating said slides.

3. An air draft control for cellular radiators of motor vehicles comprising, a plurality of rectangular shutters disposed transversely of the radiator to cover the horizontal rows of cells, means for hinging said shutters to the radiator, members mounted to slide on the radiator along the ends of the shutters, said members having diagonal slots, each of the shutters having an extension at the end thereof engaging a slot, the slots engaged by the shutters lying in the upper half being arcuate, while those engaged by the lower half are straight and have an angular extension to allow to said members an initial displacement relative to said shutters in the lower half of the radiator, said slots in the lower half being at such an angle as to cause a more rapid displacement of the shutters in the lower half than that caused by the arcuate slots, and means for actuating said members.

4. An air draft control for cellular radiators of motor vehicles, comprising a plurality of shutters adapted to cover the horizontal rows of air cells, members mounted to slide on the radiator along the ends of the shutters, said members having slots, each of the shutters having an extension engaging a slot, the slots engaged by the extensions of the shutters lying in the lower half of the radiator having an angular extension, permitting to said members an initial displacement relative to said shutters in the lower half, and means for actuating said members and retaining the same in predetermined positions, said slots having the extension having an angularity such as to displace the shutters engaged therein more rapidly than the shutters engaged in the slots without the extension.

5. An air-draft control for cellular radiators of motor vehicles comprising, a plurality of horizontally-disposed shutters for obstructing the air flowing through the cells, and means for operating said shutters, including means for initially displacing the shutters disposed in the upper half of the radiator whereby the upper half of the shutters may be partially displaced without the displacement of the lower half of the shutters, said latter means including means for displacing the shutters of the lower half more rapidly than the shutters of the upper half.

6. An air-draft control for cellular radiators of motor vehicles comprising, shutters for obstructing the circulation of air through the cells, and means for operating the shutters, including means for initially displacing some of said shutters, said latter means being adapted to displace the other

shutters not initially displaced more rapidly to fully operate all of the shutters.

7. An air-draft control for cellular radiators of motor vehicles comprising, shutters for obstructing the circulation of air through the cells, and means for operating all of said shutters, including means for initially operating some of the shutters.

8. An air-draft control for cellular radiators of motor vehicles comprising, shutters for obstructing the circulation of air through the cells, and operating means for initially displacing some of said shutters and adapted to displace the other shutters not initially displaced more rapidly to fully operate all of the shutters.

9. An air-draft control for cellular radiators of motor vehicles comprising, a plu-

rality of shutters each adapted to obstruct a row of cells, slides engaging said shutters for operating the same, including means giving to said slides an initial displacement relative to some of the shutters, said means adapted to displace said shutters relative to which said slides have an initial displacement more rapidly than the other shutters whereby all of said shutters may be fully operated by the displacement of the slides, and means for actuating said slides.

In testimony whereof I have signed my name to this specification in the presence of two subscribing witnesses.
